UNITED STATES PATENT OFFICE.

FRANK DVORAK, OF DICKINSON, NORTH DAKOTA.

GATE-OPERATING MECHANISM.

1,209,271.

Specification of Letters Patent. Patented Dec. 19, 1916.

Application filed September 14, 1915. Serial No. 50,695.

To all whom it may concern:

Be it known that I, FRANK DVORAK, a citizen of the United States, residing at Dickinson, in the county of Stark and State 5 of North Dakota, have invented certain new and useful Improvements in Gate-Operating Mechanism, of which the following is a specification.

This invention relates to improvements in 10 gate operating mechanism and as its primary object aims to provide a novel device of this nature which, in addition, to opening and closing the gate will cause a simultaneous unlatching or latching thereof.

15 Another object of the invention is to provide improved means that may be so actuated as to cause the positive opening or closing movement of the gate, and means simultaneous therewith to release or retain the 20 latch bar of the gate such as the case may be, thereby making the entire operation simultaneous and obviating the delay in unlatching the gate and opening the same at different times.

25 A further object is to provide improved latch means which may be quickly actuated so as to release or retain the latch bar of the gate in an effectual manner, the said latch means being of a durable construction and so formed that it may be manufactured very 30 cheaply.

A still further object of the invention is to provide a device of the type in question, that is as a whole, extremely simple in construction and which, it is believed, may be manufactured at a minimum cost.

Various other objects and advantages will become apparent during the continuance of the following description.

40 The above and other objects which will become apparent, are accomplished by such means as are shown in their preferred form in the accompanying drawings, described in the following specification and then more 45 specifically pointed out in the appended claim.

In the accompanying drawings wherein like characters designate like parts throughout the several views; Figure 1 is a diagrammatic view of my invention as shown in its preferred embodiment. Fig. 2 is a sectional view taken on line 2-2 of Fig. 1. Fig. 3 is a view in detail showing the specific form of latch means.

50 In the drawings the numerals 10 and 11 55 designate a pair of upstanding supporting

posts that are spaced apart a suitable distance and may be anchored to the ground, such as by embedding the ends thereof in concrete or the like. A cross-piece 12 connects the upper ends of the posts 10 and 11 and is suitably braced by guy rods 13 so as to obviate lateral displacement thereof. Any suitable means may be employed to retain the lower ends of the guy rods. However in the drawings I have shown the same connection with a pair of posts 14 which project slightly above the surface of the ground.

The gate which is designated in its entirety by the numeral 15 consists of a pair of vertical end pieces 16 and 17 which are connected by a plurality of longitudinal slats 18 and a diagonally extending brace member 19. A shaft 20 extends longitudinally through the end piece 16 of the gate, its lower end 21 projecting slightly below the lower end thereof and being journaled in a bracket 22 in order to provide a bearing for the gate. The upper end of the rod 20 is in turn passed through a suitable aperture in the cross piece 12 whereby the gate structure will be held in swinging relation to the remaining mechanism.

In order to efficiently support a secondary 35 shaft 23, the cross piece 12 is provided with spaced apart brackets 24 through which the said shaft carries a gear wheel 25 which meshes with another gear wheel 26 that is keyed to the shaft 20. At its other end the 40 shaft 23 is bent to form an arm 27 that extends at substantially right angles to the general extent of the shaft. A longitudinally slotted yoke 28 is also carried by the cross piece 12, the slots 29 thereof receiving, 45 and serving as guide means for a pair of operating rods 30 and 31, the latter having their inner ends connected and formed into an upstanding projection 32 of the operating rods. However in the drawings I have 50 shown a fastening member 33 for that purpose. It will also be noted that the free ends of the operating rods are bent so as to form hand gripping portions 34.

Passing hence, more to the construction 105 of the gate, it will be noted that the end piece 17 carries a rigid latch bar 35, which, when the gate is in a closed position is disposed in close proximity to a plate 36 carried upon the post 11. In order to form 110 means for retaining the gate in a closed position, a pair of suitably curved latch mem-

bers 37 and 38 are pivotally mounted upon the plate 36 as at 39. In order to normally retain the latch members in an advantageous position, relative to the latch bar of the 5 gate, the lower ends of the same have connection as at 40 with a retractile spring 41. The spring 41 is of course mounted upon the post 11 such as shown at 42. The lower ends of the latch members 37 and 38 also have 10 connection with flexible members 43 which in turn have their upper ends connected as at 44 to a single flexible element 45. The flexible element 45 extends upwardly with respect to the post 11 and is passed through an 15 eyelet 46 which is arranged thereon and formed of a length whereby its upper end may be connected to the upstanding projection 32 of the operating rods. This structure is clearly shown in Fig. 1.

20 Now in the operation of my improved gate, assuming that the parts are in the position shown in Fig. 1, the operator applies a suitable pressure to either of the operating rods 30 or 31, either a pulling or pushing pressure, whichever is most convenient, 25 whereby the flexible element 45 will be drawn in such a manner as to rock the latch members 37 and 38 into a position whereby free movement of the latch bar is permitted. 30 Simultaneous with this operation the arm 27 is rocked so as to cause the rotation of the shaft 23 which will of course move the shaft 20 so as to cause the opening of the gate.

From the foregoing it is believed that the 35 advantages and novel features of my invention will be readily understood and therefore further detailed description is deemed unnecessary.

In reducing my invention to practice I 40 find that the form referred to herein as the most practical and preferred embodiment is the most efficient, but realizing that certain conditions will necessarily vary in occurrence with the adoption of my device, I

desire to emphasize the fact that various 45 minor changes in the details of construction and in the proportion of parts may be resorted to when required without sacrificing any of the advantages of my invention as defined in the appended claim. 50

Having thus fully described my invention, what I claim as new and desire to secure by Letters Patent is:

In a device of the character described, upstanding supporting posts, means connecting 55 said posts adjacent their upper ends, a shaft carried by one of said posts and journaled through said connecting means, said shaft extending longitudinally with respect to said posts, a gate bodily movable with said shaft and operating in a path between said posts, a secondary shaft mounted on said connecting means, a beveled gear connection between 60 said shafts, a slotted guide member on said connecting means, operating rods extending 65 through said guide means, the inner ends of said operating rods being bent to form an upstanding portion, a crank at one end of said secondary shaft, means connecting the 70 crank portion of said secondary shaft and said operating rods, whereby a forward or rearward thrust of said operating rods will cause rotation of said secondary shaft, latch means carried by one of said supporting 75 posts, means connecting said latch means and said upstanding portion of said operating rod, and means on said gate to engage said latch means when said gate is in a closed position; whereby upon moving said operating rods said gate may be opened or 80 closed and said latch means operated simultaneously.

In testimony whereof I affix my signature in presence of two witnesses.

FRANK DVORAK.
